(57) **CLAIM**

The ornamental design for a pet car seat as shown and described.

DESCRIPTION

FIG. 1 is a top perspective view of a pet car seat, showing my new design;

FIG. 2 is a bottom perspective view thereof;

FIG. 3 is a front elevational view thereof, the rear elevational view being a mirror image of FIG. 3;

FIG. 4 is a left elevational view thereof;

FIG. 5 is a right elevational view thereof;

FIG. 6 is a top plan view thereof; and,

FIG. 7 is a bottom plan view thereof.

The broken lines in the figures are for the purposes of illustrating portions of the pet car seat, which form no part of the claimed design.

1 Claim, 6 Drawing Sheets
